UNITED STATES PATENT OFFICE.

WILLIAM I. MACOMBER, OF NORWOOD, RHODE ISLAND, ASSIGNOR TO
REGNELL, BIGNEY & CO., OF ATTLEBOROUGH, MASSACHUSETTS.

MACHINE FOR MAKING CURB-CHAINS.

SPECIFICATION forming part of Letters Patent No. 645,039, dated March 6, 1900.

Application filed December 5, 1898. Serial No. 698,330. (No model.)

To all whom it may concern:

Be it known that I, WILLIAM I. MACOMBER, a citizen of the United States, residing at Norwood, in the county of Providence and State 5 of Rhode Island, have invented a new and useful Improvement in Machines for Making Curb-Chains, of which the following is a specification.

The nature of my invention consists in the 10 improved construction and arrangement of parts whereby the chain may be formed in an expeditious manner and of superior quality.

In the accompanying drawings, Figure 1 represents a top view of the machine. Fig. 15 2 represents a side elevation. Fig. 3 represents a top view with the parts in a different position from that shown in Fig. 1. Figs. 4 to 16, inclusive, represent side views and detail edge views of the several cams. Fig. 17 20 represents a section taken in the line 17 17 of Fig. 1. Fig. 18 represents the same section when the parts are in the position shown in Fig. 3. Fig. 19 represents a section taken in the line 19 19 of Fig. 3. Figs. 20 and 21 represent enlarged detail sections taken in the 25 line 19 19 of Fig. 3, showing the carrier-jaws in their reversed positions. Fig. 22 represents a section taken in the line 22 22 in Fig. 19. Fig. 23 represents an end view of the 30 slide shown in Fig. 22 for closing the rotative jaws employed for twisting the link. Fig. 24 represents a section taken in the line 24 24 of Fig. 3. Fig. 25 represents a section taken in the line 25 25 of Fig. 1. Fig. 26 represents a 35 section taken in the line 26 26 of Fig. 25. Fig. 27 represents an end view of the tool for spreading the ends of the severed wire coil upon the mandrel. Fig. 28 represents a side view of the same. Fig. 29 represents a detail side 40 view showing the wire wound upon the mandrel and the means for spreading the ends of the link, the tool for spreading the ends being in its backward position. Fig. 30 represents a rear end view of the rock-shaft for 45 holding the spreading-tool. Fig. 31 represents the parts shown in Fig. 29 with the spreading-tool brought forward. Fig. 32 represents the same with the rock-shaft turned to spread the end of the link. Fig. 33 represents a rear end view of the rock-shaft when 50 in the position shown in Fig. 32. Fig. 34 rep-

resents a rear side view of the mandrel after the withdrawal of the spreading-tool. Fig. 35 represents a detail section taken in the line 35 35 of Fig. 21, and Fig. 36 represents an end 55 view of the rock-shaft which operates the slide shown in Fig. 35. Fig. 37 represents a section taken in the line 37 37 of Fig. 20. Fig. 38 represents a section taken in the line 38 38 of Fig. 21. Fig. 39 represents an enlarged 60 plan and end view of the carrier-jaws removed from the pivotally-operated holding-guides.

In the drawings, A represents the frame or bed of the machine; B, the driving-shaft; C, the driving-pulley; D, a pinion secured to 65 the driving-shaft, and E a driven gear secured to the cam-shaft F. The wire a from which the chain is formed after passing through a guide-eye a' is wound upon the rotative mandrel G, held in the sleeve b, which 70 passes downward through the bushing c, secured by means of its flange to the underside of the table and forming a bearing for the rotation of the sleeve. The lower end of the sleeve b is provided with the pinion b', which 75 engages with the gear b², held for rotation upon the stud b³, the said gear being actuated for revolution by means of the spring-actuated ratchet-dog b⁴, loosely secured to the pivoted lever b⁵, provided at its outer end 80 with the slot b⁶, and by means of the said slot and the stud b⁷ operative connection is made with the slide b⁸, which is reciprocated by means of the adjustable crank-pin b⁹ and the connecting-rod b¹⁰, whereby the mandrel G 85 will be caused to make one complete revolution for winding the wire to form the link at each revolution of the cam-shaft F. Upon the backward movement of the ratchet-dog b⁴ the revolving cutter H, held in the slide c², 90 will be brought forward by means of the lever c³, pivoted at the stud c⁴ and connected with the slide c² by means of the stud c⁵ and slot c⁶, the outer end of the lever c³ being actuated to carry the cutter H forward by means 95 of the sliding rod c⁷ and the cam I, the said sliding rod being held in the bearing-stands c⁸ c¹⁰, and between the bearing-stand c¹⁰ and the collar d is placed the compression spiral spring d', which serves to draw the cutter H 100 backward when the sliding rod c⁷ is released from the acting surface d' of the cam. When

the upper coil of wire upon the mandrel G has been severed by the saw H, the spreading-tool J, formed with the penetrating lip d⁸, located at one side of the axis of the sliding and rotative shaft d⁴, to which it is attached, is brought forward, as shown in Fig. 31, to cause the spreading of the ends of the severed coil d⁵ from each other, as shown in Fig. 34. The sliding and rotative shaft d⁴ is supported by the bearing-stands d⁶ d⁷ and is provided at its outer end with the crank-arm d⁸, from which operative connection is made with the cam K by means of the sliding rod d⁹, held in the guides d¹⁰ d¹⁰, the reverse rotary movement of the spreading-tool being effected by means of the compression-spring d¹¹, held upon the rod d⁹ between the guide d¹⁰ and the pin d¹², which passes through the rod. The required endwise movement of the sliding and rotative shaft d⁴ is effected by means of the lever L, which bears against the end of the said shaft and is pivoted at the stud e and actuated to carry the spreading-tool forward by means of the side cam M, which engages with the antifriction-roller e', the spreading-tool being withdrawn from the mandrel by the resilient action of the compression-spring e², which is held between the bearing-stand d⁶ and the collar e³. When the ends of the upper coil d⁵ have been thus spread from each other, the grooved jaws e⁴ e⁴ are brought forward to embrace the opposite edges of the coil preparatory to its transfer to the link closing and twisting means of the machine, the said jaws e⁴ e⁴ being arranged to slide back and forth between the pivotally-operated holding-guides e⁵ e⁵, being connected thereto by means of screw-studs e⁶, which pass loosely through slots e⁷ in the end portions of the holding-guides, as shown in Figs. 17 and 18. The grooved jaws e⁴ e⁴ are secured to each other by means of the cross-bar e⁸ and the adjusting-screw e⁹, by means of which the space between the jaws e⁴ e⁴ may be adjusted to properly fit the sides of the link.

The holding-guides e⁵ e⁵ are not connected with each other, but are actuated conjointly to make a semirevolution upon their pivot-axes f f, which are loosely held in the fixed lugs f' f', projecting upward integrally from the bed A, by means of the cams N N, which operate upon the antifriction-rollers f² f² of the sliding bars f³ f³, which are provided with the downwardly-extending slotted ends f⁴ f⁴, from which by means of studs f⁵ f⁵ operative connection is made with the levers f⁶ f⁶, pivoted to the lugs f' f' and provided with the segment-gears f⁷ f⁷, which engage with the pinions f⁸ f⁸, secured upon the pivot-axes N N. The required sliding movement of the jaws e⁴ e⁴ within the holding-guides e⁵ e⁵ is effected by means of the slide f⁹, to which the brackets g g' are secured by means of the

screws g², as shown in Fig. 20, and the desired reciprocating movement is imparted to the slide f⁹ by means of the rock-shaft g³, provided with an enlarged end bearing g⁴ in the lug f' and with an eccentric-pin g⁵, which enters a vertical groove g⁶ in the edge of the slide f⁹, and the required rotative movement is imparted to the rock-shaft g³ by means of the cam O upon the shaft F, the said cam being arranged to act upon the engaging end g⁷ of the sliding bar g⁸, held in the bearing-stands g⁹ g⁹ and actuated outwardly from the shaft F by means of the spiral spring h, which is held upon the sliding bar g⁸ between the bearing-stand g⁹ and the cross-pin h', the outer end of the sliding bar g⁸ being connected to the crank-arm h², secured to the end of the rock-shaft g³. When the jaws e⁴ e⁴ are thrown over, as shown in Fig. 21, to remove the severed coil d⁵ from the winding-mandrel, the said jaws are carried forward for engagement with the said coil by the engagement of the slide-bracket g with the cross-bar e⁸, and when the sliding jaws e⁴ e⁴ are thrown over to the position shown in Fig. 20 for delivering the severed coil to the link-engaging means the sliding carrier-jaws are held in position and also carried backward out of engagement with the delivered link by the engagement of the cross-bar e⁸ with the notch h³ of the slide-bracket g'.

When the pivotally-held sliding carrier-jaws e⁴ e⁴, with the contained open coil d⁵, are turned in a vertical plane to the position shown in Figs. 19 and 20, the turning jaws h⁴ h⁵, which hold the previously-formed link at the backward position of the said jaws, are brought forward by the action of the cam P, so that the open link held in the carrier-jaws e⁴ e⁴ will engage with the closed link held in the turning jaws. Then the action of the cam Q causes the backward movement of the sliding bar h⁶, which movement will cause a corresponding movement of the lever h⁷, pivoted at the point h⁸ and having its end socketed in the edge of the sliding bar h⁹, the said sliding bar being actuated in the forward direction by means of the spiral spring i' and provided at its forward end with an upward extension i², which at its inner side forms a bearing for the end of the adjusting-screw i³ upon the shank i⁴ of the movable jaw h⁴, the said movable jaw being actuated in its opening movement by means of the spiral spring i⁵, and upon the release of the previously-formed link from the turning jaws the action of the cam P upon the socketed antifriction-ball i⁶ will cause the forward movement of the turning jaws to seize the link held in the carrier-jaws, and upon such seizure the open ends of said link will be closed together between the said jaws. Then the backward movement of the carrier-jaws by the action of the cam O upon the slide-bracket g' will serve to release the link from the carrier-jaws, and then the action of the cams N N will serve to throw the carrier-jaws back to the winding-mandrel for the recep-

tion of another severed coil of the wire, and while the carrier-jaws e^4 e^4 are being thus thrown to their backward position the intermediate holding-jaws j j' are turned from their downward position (shown in Figs. 19 and 20) to their upright engaged position, (shown in Fig. 21,) the said holding-jaws being held upon the hollow rock-shaft j^2 , the jaw j being rigidly secured thereto, while the jaw j' is pivoted to the jaw j at the point j^3 , the said jaws being operated in their opening movement by means of the spiral spring j^4 and in their closing movement by means of the sliding rod j^5 , which is prevented from turning by suitable means and has an inclined end j^6 , adapted to operate the jaw j' in its closing moment, the said jaw being provided with the shank j^7 , in which is placed the adjusting-screw j^8 , against which the inclined surface j^6 is caused to act to close the jaws by means of the side cam R , which operates upon the antifriction-roller j^9 at the end of the lever k , pivoted at the point k' and operating to throw the sliding rod j^5 inward, the said rod being actuated in its outward direction by means of the spiral spring k^2 . To the end of the hollow shaft j^2 is secured the crank-arm k^3 , and to the outer end of the said crank-arm is connected the sliding bar k^4 , held in the bearing-stands k^5 k^5 and provided at its outer end with the antifriction-roller k^6 for engagement with the internal edge cam S , and by means of the said cam and the opposing spring k^7 the jaws j j' are actuated in their forward and backward movement. When the closed link i is being held between the turning jaws h^4 h^5 and the holding-jaws j j' , a quarter of a turn will be imparted to the turning jaws by means of the cam T upon the shaft F , the lever k^8 , pivoted to the table at the stud k^9 , provided with the antifriction-roller l^6 and actuated toward the cam by means of a coiled torsion-spring m , (shown enlarged in Fig. 24,) the jointed connecting-rod l , and the crank-arm l' , to which the said rod l is connected, the said crank-arm being secured to the bearing-sleeve l^2 , held loosely in the bearing-stand l^3 , and within the bore of the sleeve l^2 is secured the spline l^4 , which is loosely held in the longitudinal groove l^5 , made in the sliding spindle U , so that a rotative movement imparted to the sleeve l^2 will be also imparted to the spindle U , which carries at its forward end the turning jaws h^4 h^5 , and the rotative movement thus imparted to the spindle will cause the proper twisting of the link, upon the completion of which the intermediate holding-jaws j j' are released from their hold upon the link and turned to their downward position preparatory to the subsequent presentation of a new link by the action of the carrier-jaws, and as these operations are continuously performed the completed chain W will pass downward over the grooved pulley V .

65 I claim as my invention—

1. In a chain-machine, the combination of the bed or table, the winding-mandrel lo-

cated above the table, the sleeve for holding the mandrel, the pinion secured to the sleeve below the table, the gear engaging with the pinion, and ratchet means for rotating the gear, with the revolving cutter above the table, and means for moving the cutter toward and from the mandrel, for cutting off the wire coil in timely relation to the rotation of the mandrel, substantially as described.

2. In a chain-machine, the combination of the intermittently-rotated winding-mandrel, the revolving cutter for severing the wire of the coil, and means for moving the cutter toward and from the mandrel in timely relation to the rotation of the mandrel, with the grooved sliding carrier-jaws provided with the cross-bar and adjusting means, the separate pivoted holding-guides for the carrier-jaws, means for operating the pivoted holding-guides to cause the transfer of the severed coil from the mandrel to the link closing and twisting mechanism, and means for causing the forward movement of the sliding carrier-jaws within the holding-guides, at the completion of their forward and backward pivotal movements, substantially as described.

3. In a chain-machine, the combination of the intermittently-rotated winding-mandrel, a cutter for severing the wire of the coil, and means for moving the cutter toward and from the mandrel, with the pivotally-actuated sliding carrier-jaws, means for operating the same, the turning jaws, the intermediate holding-jaws, and means for operating the said holding and turning jaws, substantially as described.

4. In a chain-machine, the combination of the intermittently-rotated mandrel, a cutter for severing the wire coil, and reciprocating and rotative means for spreading the severed ends of the coil upon the mandrel, substantially as described.

5. In a chain-machine, the combination of the sliding carrier-jaws, the closing and turning jaws, and the intermediate holding-jaws, with means for causing the transfer of the open link from the carrier-jaws to the turning jaws, and for presenting the link so held to the holding-jaws, and means for twisting the link between the turning and holding jaws, substantially as described.

6. In a chain-machine, the combination of the intermittently-rotated winding-mandrel, the cutter for severing the wire of the coil, and reciprocating and rotative means for spreading the ends of the previously-severed coil upon the mandrel, with the sliding carrier-jaws, the pivotally-held holding-guides for the sliding carrier-jaws, means for imparting pivotal movement to the holding-guides and the carrier-jaws, to cause the removal of the spread coil from the mandrel and to present its opened end to the previously-formed closed and twisted link held in the turning jaws, and the turning jaws adapted to present the completely-formed twisted link for engagement

with the opened wire coil held in the pivotally-operated carrier-jaws, substantially as described.

7. In a chain-machine, the combination of 5 the intermittently-rotated winding-mandrel, the revolving cutter for severing the wire of the coil, means for spreading the severed ends of the end coil while held upon the mandrel, the pivotally-held sliding carrier-jaws 10 adapted to remove the spread coil from the mandrel and present its opened end to the previously-formed twisted link held in the turning jaws, and means for causing the pivotal turning movement of the sliding carrier-jaws, with the opposite turning jaws 15 adapted to present the completely-formed twisted link for engagement with the spread wire coil held between the carrier-jaws, means for causing the release of the completed link from the 20 turning jaws, means for causing the subsequent engagement of the turning jaws with the spread wire coil held between the carrier-jaws and for closing the ends of the wire coil between the turning jaws, and means for with- 25 drawing the sliding carrier-jaws from the closed link, substantially as described.

8. In a chain-machine, the combination of the sliding carrier-jaws adapted for pivotal movement, and the turning jaws adapted for 30 sliding and rotative movement, with the intermediate pivotally-operated holding-jaws

adapted to seize the end of the closed link after its release from the carrier-jaws, means for rotating the turning jaws to cause the twisting of the link between the holding and 35 turning jaws, and means for opening and closing the holding and turning jaws, substantially as described.

9. In a chain-machine, the combination of 40 the pivotally-operated sliding carrier-jaws, and the turning jaws, with the intermediate holding-jaws arranged transversely of the hollow shaft for pivotal movement, and a sliding rod arranged within the hollow shaft, and provided with an inclined end for actuating the 45 movable holding-jaw in the plane of its pivotal movement, to seize the end of the link released from the sliding carrier-jaws, substantially as described.

10. In a chain-machine, the combination of 50 the intermittently-operated winding-mandrel, with the pivoted holding-guides, the sliding carrier-jaws arranged between the holding-guides, the slide provided with the engaging brackets for actuating the carrier-jaws, and 55 means for operating the slide, substantially as described.

WILLIAM I. MACOMBER.
